UNITED STATES PATENT OFFICE.

COLUMBUS K. LASSITER, OF RICHMOND, VIRGINIA.

DRILLING-MACHINE.

1,087,957.

Specification of Letters Patent. Patented Feb. 24, 1914.

Application filed August 14, 1912. Serial No. 715,021.

To all whom it may concern:

Be it known that I, COLUMBUS K. LASSITER, a citizen of the United States of America, and resident of Richmond, in the county of Henrico and State of Virginia, have invented certain new and useful Improvements in Drilling-Machines, of which the following is a full, clear, and exact description.

10 This invention relates to improvements in drilling machines, and more especially to drilling machines comprising a post or upright support, and a horizontal arm supported by and revoluble through part of a circle about the post; and carrying a single or multiple drill spindles at its outer end. In machines of this kind, means are provided, at or adjacent the place where the arm is connected, revolubly, to the post for locking the former against swinging movement relatively to the latter when the arm is adjustably positioned to bring the drill spindle or spindles in proper lines relatively to the work to be drilled. Inasmuch as the 20 working place for the operator is principally at the outer drill carrying end of the arm, and in proximity to the piece to be drilled, it is a matter occasioning inconvenience and loss of time for him preparatory to nearly positioning the drill and also after such positioning to first walk to the post and unlock the arm, and thereafter to again walk to the post to relock the arm. The principal object of this invention, 30 therefore, is to provide, in conjunction with the means located adjacent the revolubly connected inner portion of the arm for detachably locking such arm to the upright support or post, a device operable on and 40 for controlling the locking means, the actuating portion of which is located adjacent the outer end of the arm.

Other objects are to provide improved locking means; and to provide efficient, 45 practical and comparatively simple means for actuating any suitable device for locking the arm to the upright support.

The invention is described in conjunction with the accompanying drawings and is defined in and by the claims.

In the drawings:—Figure 1 is a side elevation of a drilling machine understood as of large size, and with a comparatively long, horizontal revolubly swinging drill-

carrying arm and having the present arm 55 locking device, and the controlling portion of the means for operating such locking device accessible to the workman adjacent the drill carrying end of the arm. Fig. 2 is a vertical sectional view through the inner 60 portion of the arm and the portion of the upright support to which the arm is revolubly connected, and the novel parts combined therewith; Fig. 3 is a partial horizontal sectional and plan view, on line 3—3, Fig. 65 2; Fig. 4 is a sectional view through a three-way valve included in the fluid pressure controlling means for the locking device; Fig. 5 is a partial elevation illustrating a modification of the construction shown 70 in the preceding views.

In the drawings, A represents the horizontal and comparatively long drill-spindle carrying arm which is connected, for a revolubly swinging movement in a horizontal 75 plane, to the upright support therefor, here represented as comprising the post or standard B and the vertical feed slide C.

D represents the axially vertical drill spindle at the outer end of the arm and 80 over the work supporting bed E, the spindle in the particular machine represented in Fig. 1 being controlled by a hydro-pneumatic apparatus, forming no part of this invention and not necessary to be particularly referred to here, further than to state that it comprises, as an operative portion thereof, a flexible pipe F connected with an air compressor F² and having a valved connection with the hydro-pneumatic drill 85 spindle controlling arrangements.

The portion of the upright support constituted by the vertical feed slide C has upper and lower horizontally inwardly extended brackets G G provided with bushed 95 journal bearing holes a a therein.

The arm A at its inner end has vertical axially aligned upper and lower hub or trunnion-like members b b constituting journals which are fitted in the bearing holes of the 100 brackets as usual; and the arm just above its lower journal member b has a portion d of cylindrical form which is encircled by a constrictive locking ring H rigidly affixed to and supported by the vertical feed slide C. 105 The split ring has at its side opposite the feed slide the pair of outwardly extended ear lugs f f adjacent and at either side of

the cleft of the ring, the same having ratchet shaped cam surfaces g on the opposite, outer sides. The ear lugs f are horizontally penetrated by a shaft h on the extremities of which are mounted for oscillation a pair of hubs i having lever extensions j , said hubs being restrained against axial movements on the shaft by the shaft head c and nut c^2 . The said lever provided 5 hubs i have ratchet shaped cams k on their inner ends, in operative impingement against the cams g of the split ring ear lugs f .

As manifest, any rotative movement of 10 the cam faced lever hubs in one direction will force the ear lugs toward each other and cause a constriction of the ring H about the cylindrical portion of the arm, resulting in the locking of the latter against revolute movement relatively to the upright support; while, of course, the movement of 15 the cam faced hubs in the reversed direction will free the ring for its spring-reactive expansion, unlocking the arm for its revoluble movement for newly positioning the drill 20 relatively to the work.

The inner, journaled end of the arm A is made hollow to afford a chamber for occupancy therein of a plunger weight K , the lower portion of which has a guided fit 25 through an opening therefor centrally through the lower journal b . The plunger weight carries a cross bar m at its lower end pivotally connected with the extremities of which is a pair of approximately vertical links n , which are also pivotally connected to the lever-like extensions j of the cam faced members i . The plunger weight has, as an upward extension thereof, a closed 30 hollow cylinder L , down into which,—and through the packing box in its upper end,—extends a rigid pipe M , for which a support s is provided on the upper bracket G , and above the end of the hollow upper arm-journal b . This vertical rigid pipe has a 35 piston-like enlargement p at its lower end, and a port q above the part p forming communication between the pipe and the cylinder chamber.

Q represents a pipe which is coupled to and has constant communication with the pipe M and the same extends horizontally adjacent and to near the outer end of the arm A and has by short coupling pipe r a 40 connection with the aforementioned compressed air supplying pipe F . In the short coupling pipe r is a three-way valve R , the body thereof having port s in connection with compressed air supply pipe F , the opposite port t in connection with pipe Q and the relief or exhaust port u opening to the atmosphere. The partially rotary body v of the valve has the cross way v^2 so widened at its opposite ends that, as shown in 45 full lines in Fig. 4, it may open free con-

nection between pipes F and Q ; or when positioned as represented by the dotted lines it will shut off connection between pipes F and Q , but will leave pipes M , Q , open to exhaust through the port u .

The operating lever R^2 of the valve R has a vertical rod R^3 connected therewith, the same passing through a guiding eye w and having a handle at its lower end, forming an adjunct of the controlling means for the arm locking device conveniently accessible to the workman while at a position remote from the location of the lock.

Owing to the fact that the head T by which the drill spindle, or spindles are carried is movable horizontally inwardly and outwardly on the arm, and the valve R is, in effect, supported by such head, the pipes F and Q are flexible; and it is further to be understood that, in the apparatus represented in Fig. 1, while a portion of the pipe F is supported by the coupling connecting pipes Q and M , these pipes at such place of union, and of support for pipe F are closed from communication with the pipe F .

The descent of the elevated plunger K is effective through the link and lever connections to cause the constriction of the split ring to lock the arm; and when the plunger is in its lowered position for the elevation thereof to release the locking devices, the valve is turned to the position shown in Fig. 4 so that there is a passage of compressed air from the pipe F to and through the pipes Q and M , the same issuing through the port q 90 into the cylinder L , displacing the latter upwardly and with it the plunger weight K ,—it thus being seen that the establishing of pressure, by properly positioning the valve R , in and through the pipe M raises 95 and maintains the plunger weight elevated, keeping the locking device released; while to effect a locking of the arm the valve is positioned to permit the exhaust of the pressure from the cylinder and pipes M and Q , 100 leaving the plunger weight to gravitatively and forcibly operate the locking device.

Instead of operating the locking device for the arm by pneumatic means as above described, mechanical means may be utilized for this purpose; and in Fig. 5 the pair of levers j which are understood as extensions of the cam provided hubs i have a thrust rod W connected therewith which extends in substantial parallelism with and to or near the outer end of the arm and adapted to be operated manually.

This invention is susceptible of many changes of minor character, and in respect of details of construction without departing therefrom or sacrificing the advantages thereof as defined in the appended claims.

I claim:—

1. In a drilling machine, a support, having a bracket provided with a journal bear-

therein, an arm having at the inner portion thereof a journal fitting in said journal bearing, a drill carried by the outer extremity of said arm, a split ring on the support having outwardly extended lugs adjacent the cleft thereof, means coacting with said lugs for the constriction of the ring, and a device for actuating said constricting means, the controlling or operating portion of which is located adjacent the outer end of the arm.

2. In a drilling machine, in combination, an upright support, having a horizontally extended bracket provided with a vertical journal bearing hole therein, a split ring mounted on said bracket and having outwardly extended lugs adjacent the cleft thereof, a horizontal arm having at the inner portion thereof an axially vertical journal fitting in said journal bearing hole, a drill spindle carried by the outer extremity of said arm, an oscillatory member having a cam coacting with one of said lugs for the constriction of said ring, and means for oscillating said member.

3. In a drilling machine, in combination, an upright support, having a horizontally extended bracket provided with a vertical journal bearing hole therein, a split ring mounted on said bracket and having outwardly extended lugs adjacent the cleft thereof, provided with cam surfaces on their opposite faces, a horizontal arm having at the inner portion thereof an axially vertical journal fitting in said journal bearing hole, a drill spindle carried by the outer extremity of said arm, a pair of rocking members journal supported adjacent said lugs and having cam faces coacting with those on said lugs for the constriction of said ring, and means for oscillating said rocking members.

4. In a drilling machine, a support, a member connected to said support, means for locking said member against movement, a plunger, means connecting said plunger with said member locking means, means for operating said plunger for locking said member, said plunger being movable to unlock said member independently of said operating means.

5. In a drilling machine, in combination, an upright support, having a horizontally extended bracket provided with a vertical journal bearing hole therein, a split ring mounted on said bracket and having outwardly extended lugs adjacent the cleft thereof, a horizontal arm having at the inner portion thereof an axially vertical journal fitting in said journal bearing hole and formed with a cylindrical portion, a drill spindle carried by the outer extremity of said arm, an oscillatory member comprising a cam coacting with one of said lugs, and a lever, a plunger vertically movable in the inner cylindrical portion of the arm and

having an operating connection with said lever, and fluid pressure means operative to elevate the said plunger.

6. In a drilling machine, in combination, an upright support, having a horizontally extended bracket provided with a vertical journal bearing hole therein, a split ring mounted on said bracket and having outwardly extending lugs adjacent the cleft thereof, a horizontal arm having at the inner portion thereof an axially vertical journal fitting in said journal bearing hole and formed with a cylindrical portion encircled by said split ring, a drill spindle carried by the outer extremity of said arm, an oscillatory device comprising a cam coacting with one of said lugs, for the constriction of the ring, a plunger vertically movable in the inner portion of the arm and having operating connection with said cam provided oscillatory device, fluid pressure means cooperative with and for vertically moving said plunger in the arm comprising a conduit extended to a point adjacent the outer end of the arm and provided thereat with a controlling valve.

7. In a drilling machine, in combination, an upright support, a horizontal arm having the inner portion thereof revolvably connected to the upright support and also made hollow, a drill spindle carried by the outer extremity of said arm, means located adjacent the revolvably located inner portion of the arm for detachably locking the latter against revoluble movement, a plunger weight within the hollow arm and operatively connected with said locking device, fluid pressure means for elevating the plunger weight comprising a hollow cylindrical extension of such weight, a stationary vertical pipe having at its lower extremity a piston-like enlargement relatively to which said cylindrical extension is telescopically movable, and such pipe having a port opening into the cylinder, and means connecting said pipe with a compressed air supply and a conduit connected with said pipe, and extended to a point adjacent the outer end of the arm, and provided thereat with a relief or exhaust valve.

8. In a drilling machine, in combination, an upright support, a horizontal arm having the inner portion thereof revolvably connected to the upright support and also made hollow, a drill spindle carried by the outer extremity of said arm, means located adjacent the revolvably located inner portion of the arm for detachably locking the latter against revoluble movement, a plunger weight within the hollow arm and operatively connected with said locking device, fluid pressure means for elevating the plunger weight comprising a hollow cylindrical extension of such weight, a stationary vertical pipe having at its lower extremity a pis-

ton-like enlargement relatively to which
said cylindrical extension is telescopically
movable, and such pipe having a port open-
ing into the cylinder, a conduit connected
5 with said pipe and extended to a point ad-
jacent the outer end of the arm, a com-
pressed air supply pipe, coupled with said
conduit, and valve means for alternately
establishing communication between the

supply pipe and said conduit, and for both 10
closing such communication and opening the
conduit to air exhaust.
